FLEXIBLE ENVELOPE FOR THE STORAGE OF LIQUIDS

Joel Sisco, Passaic, N. J.

Application August 29, 1955, Serial No. 37,697

Term of patent 14 years

(Cl. D58—2)

Fig. 1.

Fig. 2.

Fig. 1 is a top plan view of a flexible envelope for the storage of liquids shown in unfolded position and embodying my new design; and

Fig. 2 is an end elevational view thereof shown in folded position.

I claim:

The ornamental design for a flexible envelope for the storage of liquids, as shown.
